HEAT RADIATING DEVICE

Filed Aug. 28, 1930

FIG. 1.

FIG. 2.

INVENTOR:
Horace E. Whitten.

CHARLES S. GOODING,
Attest.

UNITED STATES PATENT OFFICE

HORACE E. WHITTEN, OF SOMERVILLE, MASSACHUSETTS

HEAT RADIATING DEVICE

Application filed August 28, 1930. Serial No. 478,395.

This invention relates to an improvement in heat radiating devices and has for its object to provide a device that may be located in a recess provided in the wall of a building where it is concealed from view, but nevertheless can radiate heat effectively to an adjacent room.

Another object of the invention is to provide a device that may be easily cleaned, the heat conducting member containing the flues being detachable from the heat radiating member, thereby making it possible to easily remove deposits of dust from both the radiating member and the conducting member.

Still another object of the invention is to so construct the compartment for the heating medium that condensation cannot collect therein, thereby eliminating the noises that are caused by steam passing through the radiating member contacting with water that is trapped within the radiator.

The invention consists in a heat radiating device as set forth in the following specification and particularly as pointed out in the claims thereof.

Referring to the drawings:-

Fig. 1 represents a partial front elevation and partial central vertical section of a heat radiating device embodying my invention.

Fig. 2 is a transverse section taken on the line 2—2 of Fig. 1.

Like numerals refer to like parts throughout the several views of the drawings.

In the drawings, 5 represents a heat radiating member provided with a compartment 6 therein for a heating medium and embodying therein a plurality of heat radiating flanges 7. The flanges 7 extend entirely around the heat radiating member 5 and are preferably circular in form, although they may be shaped otherwise if desired.

The heating compartment 6 extends entirely through the radiating member 5 and has a semi-cylindrical bottom surface 8 which permits condensation water to flow outwardly therefrom at its opposite ends into pipes 9 and 10 that are connected thereto, said pipes being the pipes that are utilized to conduct the heating medium, which is pref-

erably steam, to and from the radiating member. The upper portion of the heating compartment 6 is recessed at 11 within the flanges 7, thereby increasing the area of the compartment.

Mounted upon the radiating member 5 is a heat conducting member 12, preferably constructed of sheet metal, and the lower edge of each end wall of said heat conducting member is cut away at 13 to permit said edge to rest upon the body portion of the radiating member between the flanges 7. The heat conducting member 12 embodies therein a plurality of transverse partitions 14 which divide the interior of said member into a plurality of separate flues 15 and said partitions are so spaced that there will be a partition located in the space between each pair of flanges 7, and the lower edges of all of said partitions are so formed that they will rest upon that portion of the body of the heat radiating member that is located between the flanges 7. An opening 16 is provided at the bottom of each flue 15 in order that air circulating around the flanges 7 may pass upwardly through the flues 15 and the latter, at their upper extremities, are open at 17 in order that the heated air may pass outwardly therefrom at the top. The heat conducting member 13 is prevented from tipping upon the radiating member 5 by reason of the fact that the side walls of the member 12 frictionally engage the periphery of the flanges 7 at 18. Standards 19 support the heat radiating member 5 adjacent to its opposite ends.

The device when in use is located in a recess provided in the walls of a building behind a suitable ornamental grill through which the heated air is radiated by the device, and the fresh air that contacts directly with the flanges 7 passes upwardly through the various flues and is discharged at the top of the heat conducting member 12 through the discharge orifices 17, the latter preferably being located adjacent to the openings in the grill through which the air passes. As the heat conducting member 12 rests upon and contacts with the body portion of the heat radiating member 5 between the flanges 100

7, it is maintained at a relatively hot temperature and, therefore, aids in maintaining the temperature of the heated air while the latter is being conducted therethrough to the 5 grill. Furthermore, as the heat conducting member is secured to the heat radiating member 5 by frictional contact only, all that is necessary in cleaning both of said members is to remove the conducting member from the 10 radiating member and when said members are thus separated they may both be easily dusted.

The construction of the interior of the heating compartment 6 is such that water 15 cannot collect within said compartment so that noises that are usually created by steam passing through a radiating member and contacting with water that is trapped therein will be prevented.

20 I claim:

1. A device of the character described comprising, in combination, a heat radiating member provided with a compartment therein for a heating medium and embodying 25 therein a plurality of heat radiating flanges, and a heat conducting member adapted to rest upon said radiating member and provided with a flue extending therethrough above each of said flanges.

30 2. A device of the character described comprising, in combination, a heat radiating member provided with a compartment therein for a heating medium and embodying 35 therein a plurality of heat radiating flanges, and a heat conducting member adapted to rest upon said radiating member and embodying therein a plurality of partitions positioned between said flanges thereby forming flues above said flanges, whereby heat 40 radiating from said flanges may pass through said flues.

In testimony whereof I have hereunto set my hand.

HORACE E. WHITTEN.
